United States Patent Office

Des. 178,488
Patented Aug. 14, 1956

178,488

PORTABLE DISPLAY RACK

Gordon Beh, Rockville Centre, N. Y., assignor to Beh & Co., Inc., New York, N. Y., a corporation of New York

Application November 4, 1955, Serial No. 38,726

Term of patent 7 years

(Cl. D80—9)

FIG. 1.

FIG. 2.

FIG. 3.

Fig. 2 is an end elevational view, and

Fig. 3 is a side elevational view.

I claim:

The ornamental design for a portable display rack, substantially as shown.
